TAPERED MAGNETIC CORE

William E. Newman, Moorestown, N. J., assignor
to Radio Corporation of America, a corpora-
tion of Delaware

Application March 24, 1943, Serial No. 480,342

5 Claims. (Cl. 175—21)

1

This invention relates to variable permeability tuning apparatus for use in radio and analogous systems for the communication of intelligence.

In variable inductance devices of the type wherein inductance variations are effected by the movements of a magnetic core, with respect to an inductance coil, it is common practice to employ a core of tapered construction in order to achieve a desired relation between the total tuning movement or "stroke" and the inductance variation. Where, as is usually the case, the coil is mounted upon a hollow form of uniform diameter and the core is mounted for movement in or through the interior of the coil-form, a conventionally tapered core may tilt or wobble within the bore of the form. Such undesired displacement of the core within the coil-form may cause the tuning mechanism to jam or to give rise to other less apparent mechanical and electrical difficulties.

Accordingly, the principal object of the present invention is to provide an improved variable permeability tuner of the type employing a tapered core, and one which obviates the foregoing and other objections to present day permeability tuners.

Another and related object of the present invention is to provide an improved "tapered" magnetic core of novel construction and one capable of use with a standard coil and form of conventional shape and dimensions.

Another and important object of the present invention is to provide an improved "tapered" magnetic core, and one which lends itself readily to the adjustment of its effective permeability, and this, too, without change in its overall dimensions.

The foregoing and related objects are achieved in accordance with the invention in a cylindrical magnetic core of uniform overall dimensions by providing the core with one or more axially extending grooves or flutes of gradually varied depth and/or width and which may be separated one from another either by common arris or by a narrow fillet upon which the core slides within the coil-form. The permeability of cores made in accordance with the present invention may be adjusted, at least over a limited range, by applying a quantity of comminuted magnetic material (e. g., iron or the ore magnetite) in a plastic carrier (e. g., polystyrene) into one or more of the grooves or flutes.

Certain preferred details of construction will be apparent and the invention itself will be best understood by reference to the accompanying drawing, wherein:

2

Figure 1 is a plan view looking into the leading end of a magnetic core constructed in accordance with the principle of the invention.

Figure 2 is a longitudinal sectional view taken on the line II—II of Figure 1, and

Figure 3 is a projected side elevational view of the core of Figures 1 and 2.

Figure 4 is a plan view looking into the leading end of another magnetic core within the invention.

Figure 5 is a longitudinal sectional view taken on the line V—V of Figure 4, and

Figure 6 is a projected side elevational view of the magnetic core of Figures 4 and 5.

Figure 7 is a plan view looking into the leading end of a modification of magnetic core within the invention, and

Figure 8 is a projected side elevational view of the core of Figure 7.

Figure 9 is a plan view, partly in section, of a variable permeability tuner incorporating a magnetic core within the invention.

In the drawings, wherein like reference characters designate the same or corresponding parts in all figures, M (M₁, M₂, etc.) designates generally a magnetic core, which is cylindrical in outline, and constituted of mutually insulated comminuted particles or granules of the ore magnetite or of powdered iron, molded in a known manner. The diameter of the core M is such as to give it a sliding fit within the bore of its coil-form F (see Figure 9) when a suitable force is applied thereto as through a threaded brass rod R (Figures 2, 3, 5, 6 and 8) or through a pair of oppositely located eyelets E (Figure 9) which are embedded in the core prior to the molding operation.

Substantially any desired relation between the total tuning movement or "stroke" of the core and the resulting change of inductance of the coil with which it is associated is achieved, in accordance with the invention, by providing the core with one or more longitudinal flutes or grooves of gradually varied depth and/or width. Thus, in the embodiment of the invention shown in Figures 1, 2 and 3 the magnetic core M is provided with four longitudinally extending circumferentially spaced grooves G, which are separated one from another by narrow fillets T which serve to prevent the core from tilting while it is within its coil form. In this embodiment of the invention the grooves G have substantially flat bottom surfaces and are tapered both as to width and depth from the leading end of the core, where 55 the grooves are of maximum width and depth,

to points adjacent to the opposite or trailing end of the core. These grooves are preferably formed in a complementarily shaped mold (not shown); in which case the mold may be parted along a line (a—a, Figure 1) which coincides with the maximum diameter of the core.

In the embodiment of the invention shown in Figures 4, 5 and 6, the magnetic core, which is here designated M1, is provided with but two flutes G1 which are separated one from another by relatively wide fillets T1. These flutes G1 unlike the flat grooves G of the core of Figures 1-3, are curved laterally and longitudinally to provide a desired variable inductance-characteristic for the coil assembly for which the core is designed. As in the earlier described embodiment of the invention the maximum depth of the flutes or grooves G1 is adjacent to the leading end of the core.

The magnetic core M2 shown in Figures 7 and 8 is provided with three depressions or grooves G2 which terminate in three equally spaced rounded edges T2 at the leading end of the core, as shown in Figure 7. Since, as above indicated, the contour and dimensions of the grooves, as well as their number, will ordinarily be chosen with regard to the particular inductance-changing characteristic desired, it will be apparent that these grooves G2 may be either flat or curved and may be of uniform (instead of tapered) width, if desired.

Figure 9 shows a variable permeability tuner incorporating a "tapered" magnetic core M3 constructed in accordance with the principle of the invention. This core is mounted for movement within and with respect to a tuning coil A which is wound upon an open-ended coil form F of uniform diameter. The core M3 is driven by a cord B which extends around a pair of pulleys C and carries an index or pointer D which cooperates with a suitably calibrated elongated dial scale E. The core M3 and, hence, the pointer D are moved by means of a tuning knob, not shown, but which may be mounted on the end of a tuning shaft S.

The length of the magnetic core M3 and of the inductance coil A and dial scale E may be the same as disclosed in co-pending application, Serial No. 460,303, to Wendell L. Carlson, filed September 30, 1942, now Patent No. 2,370,714, granted March 6, 1945. That is to say, when an elongated dial scale is employed the length of the magnetic core M3 is preferably made at least twice that of the coil A to avoid the use of a gear train, or the like for correlating the stroke of the variable inductor with that of the tuning index or pointer D.

It is well known that small variations in the amount or quality of the core materials may result in variations in the magnetic properties of the cores. To compensate for such variations it has heretofore been proposed to attach a suitable quantity of magnetic material in the form of a pellet to the leading end of the core. Since a cavity or other auxiliary means must be pro-

vided for holding the pellet in position, this prior art method of adjusting the effective permeability of a magnetic core is not always practical, especially in the case of a core provided at its ends with a screw or with eyelets or other adjusting means. As shown in Figure 9 the permeability of a grooved core within the present invention may be adjusted by applying a small quantity of comminuted magnetic material, such as powdered iron or magnetite, in an adhesive or plastic carrier, such as polystyrene, into one or more of the flutes or grooves G3 as indicated at X.

From the foregoing it is apparent that the present invention provides an improved "tapered" magnetic core characterized by its novel construction, its ease of adjustment, and by its trouble-free performance.

What is claimed is:

1. A magnetic core adapted for insertion into a coil form which has a cylindrical bore therein, said core comprising a cylindraceous element having a maximum diameter throughout the greater portion of its length corresponding substantially to the diameter of said bore and provided with a longitudinally extending depression of tapered depth on the surface thereof which is presented to the inner surface of the bore of said coil form.
2. The invention as set forth in claim 1 and wherein the maximum depth of said longitudinal depression is adjacent to the end of said element which is first presented to said coil form.
3. The invention as set forth in claim 1 and wherein said longitudinal depression is of tapered width, and the maximum width of said depression is adjacent to the end of said element which is first presented to said coil form.
4. A device of the character described comprising a tapered core constituted of mutually insulated magnetic particles and provided on its tapered surface with a plurality of longitudinally extending raised portions for guiding said core within the bore of a coil form.
5. A magnetic core adapted for insertion into a coil form which has a cylindrical bore therein, said core comprising a cylindraceous element having a maximum diameter throughout the greater portion of its length corresponding substantially to the diameter of said bore, whereby said core has a sliding fit within said core, and provided on its outer surface with a longitudinally extending depression of axially non-uniform tapered depth.
